(57) CLAIM

The ornamental design for a chandelier, as shown and described.

DESCRIPTION

FIG. 1 is a top, front perspective view of a chandelier embodying my new design;

FIG. 2 is a bottom, rear perspective view thereof;

FIG. 3 is a top view thereof;

FIG. 4 is a side view thereof; and,

FIG. 5 is a bottom view thereof.

The broken line showing of simulative candles is included for the purpose of illustrating only and forms no part of the claimed design.
